WOOD MUSICAL INSTRUMENT GAUGE

Saul Fromkin, 409 E. 31st St.,
Paterson, N.J. 07504

Filed Dec. 1, 1967, Ser. No. 9,607

Term of patent 14 years

U.S. Cl. D52—6
Int. Cl. D10—08

FIG. 1 is a top perspective view of the wood musical instrument gauge, showing my new design,

FIG. 2 is a top plan view thereof,

FIG. 3 is a side elevational view with the measuring stick fully extended downwardly, and

FIG. 4 is a bottom plan view thereof.

The broken line portion of the mouth end of a wood musical instrument is disclosed for purposes of illustration only.

I claim:

The ornamental design for a wood musical instrument gauge, substantially as shown and described.
